UNITED STATES PATENT OFFICE.

MAX F. ABBÉ, OF NEW YORK, N. Y.

FEEDING DEVICE FOR BALL-MILLS.

No. 845,992.

Specification of Letters Patent.

Patented March 5, 1907.

Application filed September 21, 1906. Serial No. 335,556.

To all whom it may concern:

Be it known that I, MAX F. ABBÉ, a citizen of the United States, residing at New York city, Manhattan, county and State of New York, have invented new and useful Improvements in Feeding Devices for Ball-Mills, of which the following is a specification.

This invention relates to a feeding device for tubular ball-mills, which is adapted to be attached to the outer end of the hollow trunnion of said mill, so that all interior fittings for feeding purposes may be dispensed with.

In the accompanying drawing, Figure 1 is a longitudinal section through the ingress-head of a ball-mill embodying my invention; Fig. 2, a section on line 2 2, Fig. 1; and Fig. 3, a section on line 3 3, Fig. 1.

The ingress-head 10 of the mill 11 is provided with an outwardly-extending hollow trunnion 12, journaled in bearing 13. To the outer end of trunnion 12 is adapted to be coupled the feeding device made in the form of a cylindrical casing having an outer wall 14, an inner wall 15, and an intermediate partition 16. Between outer wall 14 and partition 16 is formed a feed-chamber 17, communicating with feed-pipe 18, that enters chamber 17 through a central perforation 19 in wall 14. Between partition 16 and inner wall 15 is located a spiral conveyer 20, having convolutes of gradually-decreasing diameter and receiving the material to be ground from chamber 17 through a series of peripheral openings 21 in partition 16. The innermost convolute 22 of conveyer 20 is flaring and communicates with the bore 23 at the outer end of trunnion 12, with which it registers, the diameter of the inner end of the flaring convolute being equal to that of bore 23. From inner wall 15 extends an annular flange 24, which projects over end of trunnion 12 and is bolted thereto, as at 25. The entire feeding device—viz., the casing with its partition, conveyer, and attaching flange—is made integral, so that strength is insured. The material to be reduced is fed from pipe 18 into chamber 17 and thence through openings 21 into conveyer 20, that 50 discharges it through hollow trunnion 12 into the mill.

It will be seen that my improved feeding device may be readily coupled to hollow trunnion ball-mills as now in operation without opening the same or altering their inter-

ior construction. So, also, all stuffing-boxes between the feeder and the mill are entirely dispensed with, while the feeder is readily accessible for the purpose of inspection or repair.

I claim—

1. A ball-mill having a hollow trunnion, combined with an exterior cylindrical casing composed of a perforated outer wall, an inner wall, an intermediate perforated partition, a feed-chamber between outer wall and partition, a spiral conveyer between partition and inner wall, said conveyer having a flaring central convolute that opens directly into the outer end of the hollow trunnion, and means for coupling the casing to said trunnion, substantially as specified.

2. A ball-mill having a hollow trunnion, combined with an exterior cylindrical casing composed of a perforated outer wall, an inner wall, an intermediate perforated partition, a feed-chamber between outer wall and partition, a spiral conveyer between partition and inner wall, an annular flange on the inner wall that projects over said trunnion, and means for securing said flange to said trunnion, substantially as specified.

3. A ball-mill having a hollow trunnion, combined with an exterior cylindrical casing fast on the outer end of the trunnion, and a spiral conveyer carried by the casing and having convolutes of gradually-decreasing diameter, the central convolute of said conveyer communicating directly with the outer end of the trunnion, substantially as specified.

4. A ball-mill having a hollow trunnion, combined with an exterior cylindrical casing fast on the outer end of the trunnion and composed of a perforated outer wall, an inner wall, an intermediate perforated partition, a feed-chamber between outer wall and partition, and a spiral conveyer between partition and inner wall, said conveyer having convolutes of gradually-decreasing diameter, the central convolute of said conveyer communicating directly with the outer end of the trunnion, substantially as specified.

Signed by me at New York city, (Manhattan,) New York, this 20th day of September, 1906.

MAX F. ABBÉ.
